(57) **CLAIM**

The ornamental design for a portable printer, as shown and described.

DESCRIPTION

FIG. 1 is a front perspective view of a portable printer showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof;

FIG. 8 is a left side elevation view thereof;

FIG. 9 is an enlarged front perspective view of the portable printer shown in FIG. 1, showing the claim separated from the portable printer in order to show aspects of the design that are not otherwise apparent;

FIG. 10 is an enlarged rear perspective view thereof;

FIG. 11 is an enlarged bottom perspective view thereof;

FIG. 12 is a cross section view taken at line 12-12 in FIG. 9;

FIG. 13 is a cross section view taken at line 13-13 in FIG. 9;

FIG. 14 is a top plan view of the portable printer, showing the claim in a stored state; and,

FIG. 15 is a rear perspective view thereof, showing the claim in a stored state.

The dot dash broken lines immediately adjacent to the claim represent the bounds of the claimed design while all other broken lines are directed to environment and are for illustrative purposes only; the broken lines form no part of the claimed design.

The unshaded surfaces that directly adjoin the claimed solid line edges form no part of the claimed design.
